CLAIM

The ornamental design for a portable automated external defibrillator, as shown and described.

DESCRIPTION

FIG. 1 is a perspective view of a portable automated external defibrillator showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is rear perspective view thereof; and,

FIG. 9 is another perspective view thereof showing how the device can be used.

The broken lines show portions of the portable automated external defibrillator that form no part of the claimed design. The broken lines showing the human figure in FIG. 9 represent environmental subject matter and are for illustrative purposes only.
